UNITED STATES PATENT OFFICE.

WALTER G. HASTINGS, OF BATTLE CREEK, MICHIGAN.

ABRADANT-SUPPLYING APPARATUS.

1,390,128.

Specification of Letters Patent. Patented Sept. 6, 1921.

Application filed April 12, 1920. Serial No. 373,119.

To all whom it may concern:

Be it known that I, WALTER G. HASTINGS, a citizen of the United States, residing at Battle Creek, county of Calhoun, State of Michigan, have invented certain new and useful Improvements in Abradant-Supplying Apparatus, of which the following is a specification.

This invention relates to improvements in abradant supplying apparatus for grinding and polishing machines.

My improved abradant supplying apparatus is especially designed by me for the grinding and polishing of lenses and I have illustrated the same in the accompanying drawing as I have embodied or adapted the same for that purpose. My improvements are, however, adaptable for use in grinding and polishing in other relations.

20 The main objects of this invention are:

First, to provide an improved abradant supplying apparatus which is automatic in its operation.

Second, to provide an improved abradant supplying apparatus of large capacity.

Third, to provide an improved abradant supplying apparatus which is comparatively simple and economical in structure and very convenient to use.

30 Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a 40 part of this specification, in which:

Figure I is a perspective view of my improved grinding and polishing machine, the table being partially broken away.

Fig. II is a detail horizontal section on a 45 line corresponding to line 2—2 of Fig. III.

Fig. III is a detail view partially in vertical section on a line corresponding to line 3—3 of Figs. I, II and IV.

Fig. III^a is a detail section corresponding 50 to that of Fig. III, showing the pump actuating member in its operative position, it being shown in inoperative position in Fig. III.

Fig. IV is a detail view partially in vertical section on a line corresponding to line 55 4—4 of Figs. II, III and V.

Fig. V is a detail horizontal section on a line corresponding to line 5—5 of Fig. IV, showing details of the abradant feed timing means.

Fig. VI is a detail vertical section on a line corresponding to line 5—5 of Fig. V.

Fig. VII is a detail view partially in section on a line corresponding to line 7—7 of Fig. II, showing details of the means for regulating the stroke of the grinding arm.

Fig. VIII is a detail horizontal section on a line corresponding to line 8—8 of Fig. III, showing the arrangement of the pump discharge.

Fig. IX is a detail side elevation of the pump discharge, parts being broken away to show structural details.

Fig. X is an enlarged detail of the pump, mainly in vertical central section.

In the drawing, similar reference characters refer to similar parts throughout the several views, and the sectional views are taken looking in the direction of the little arrows at the ends of the section lines.

Referring to the drawing, 1 represents the top of a table or work bench. The driving spindle 2 is arranged vertically through the table 1 and is provided with a head 3 constituting a support for the abradant receptacle 4.

When the machine is employed for grinding lenses, an abradant such as jeweler's rouge is satisfactory.

At one side of the receptacle is a pair of uprights 5 having a bracket 6 adjustably mounted thereon, the bracket being provided with a slide 7 engaging the uprights and adjustably secured by means of the set screw 7'.

On this bracket is a frame 8 provided with an agitator 9 so that as the receptacle is revolved, the abradant is stirred and kept in suspension. The pump cylinder 10 is mounted on this frame and is provided with an inlet opening 11 having a check valve 12, the inlet being provided with a screen 13.

The discharge 14 of the cylinder is connected to the passage 15 formed in the frame 8. A check valve 16 is provided for the discharge of the cylinder. The pump discharge is provided with a nozzle 17 directed so that the abradant is delivered to the grinding disk 18 on the upper end of the work spindle 19 or to the work as may be desired. The driving means for the work spindle are not illustrated as they form no

part of this invention. The plunger 20 of the pump is provided with a bifurcated rod 21 connected at 22 to the pump actuating lever 23 which is pivoted on the frame 8 at 24. The plunger actuating spring 25 engages the lever while its upper end engages the arm 26 on the frame 8.

The head 3 is provided with a circular spiral actuating cam 27, the face 28 of which is inwardly beveled as shown. The actuating member 29 is pivoted at 30 on a horizontal pivot carried by the support 31. The support is pivoted at 32 on a vertical pivot so that the actuating member has a 15 horizontal as well as a vertical movement.

The actuating member is connected to the pump lever 23 by the link 33 and is adapted to coact with the cam 27, the actuating lever being beveled at 34 to correspond with the bevel of the cam so that when the actuating member is engaged with the cam, it is retained against lateral disengagement. When the actuating member drops from the high point 35 of the cam 27, the spring 25 20 actuates the pump and delivers a charge of the abradant to the work.

A timing or control means is provided in order that the delivery of the abradant may be varied as the work requires. This in the 30 structure illustrated comprises a plurality of timing cams 36, 37, 38 and 39 having varying numbers of recesses 40—see Figs. V and VI.

The control rock shaft 41 is provided with an arm 42 adapted to ride on these cams and when it drops into the recesses, the control arm 43 is actuated to shift the actuating member to operative position as shown in Fig. III^A. The control arm has an extension 44 against which the actuating member is normally held by the spring 45 one end of which is connected to the control arm and the other to the actuating member. The actuating member is supported by the 45 rest 46 when in its inoperative position.

When the control rock shaft is actuated by its arm or dog 42 dropping into a recess of one of the timing cams, the actuating member is shifted into position to be engaged by the cam 27 and is retained in engagement therewith as described until released at passing over the high point 35 when the spring 45 returns it to its inoperative position.

The arm 42 is splined to the shaft 41 so that it may be adjusted to bring the arm into coacting relation with the desired controlling cam or timing member. The adjustment is effected through the rod 47 which 60 projects through the slotted keeper plate 47' notched to receive the rod—see Figs. I and VI.

The shaft 48 of the timing cams is provided with the worm gear 49 meshing with 65 a worm 50 on the driving spindle 2.

The grinding arm 51 is provided with the usual pin 52 and is pivoted at 53 upon the oscillating support 54. This support is provided with an arm 55 slotted at 56 to receive the clamping screw 57 provided with a clamping nut 58 so that the connecting rod 59 may be adjusted to vary the stroke 70 of the grinding arm. The connecting rod engages the eccentric 60 on the driving spindle 2.

A weight 61 provides pressure for the grinding arm.

With the parts thus arranged, I provide a grinding or polishing means for lenses and the like which is very efficient and produces high class work. The abradant is delivered in measured charges and in the desired quantities.

I have illustrated and described my improvements as I have adapted or embodied the same for grinding or polishing lenses. My improvements may, however, be adapted for use in other relations. I have not attempted to illustrate or describe such adaptations as I believe the disclosure made 85 will enable those skilled in the art to which my invention relates to modify or adapt the same as may be desired.

Having thus described my invention, what I claim as new and desire to secure by Letters Patent is:

1. In a structure of the class described, the combination of a driving spindle provided with a head, a circular spiral inwardly beveled actuating cam on said spindle head, an abradant receptacle mounted on said head within said cam, a frame member depending into said receptacle, an agitator on said frame member, a pump mounted on said frame member, a pump actuating lever pivoted on said frame member, an actuating spring for said pump lever, a pivotally mounted actuating member beveled to coact with said actuating cam, a link connecting said actuating member to said pump lever, a plurality of timing cams, driving connections therefor to said driving spindle, a rock shaft provided with an adjustable arm coacting with said timing cams, a control arm on said rock shaft coacting with said actuating member to move it to position to coact with said actuating cam, and a spring connecting said actuating member and control arm so that when the actuating member is released from the actuating cam, it is returned to its inoperative position.

2. In a structure of the class described, the combination of a driving spindle provided with a head, a circular spiral actuating cam on said spindle head, an abradant receptacle mounted on said head within said cam, a frame member depending into said receptacle, an agitator on said frame member, a pump mounted on said frame member and provided with a discharge directed to de- 130

liver to the work, a pump actuating lever pivoted on said frame member, an actuating spring for said pump lever, a pivotally mounted actuating member coacting with 5 said actuating cam, and a link connecting said actuating member to said pump lever.

3. In a structure of the class described, the combination of a driving spindle, an actuating cam on said driving spindle, an abradant 10 receptacle mounted to rotate therewith, an agitator depending into said receptacle, a pump, a pump actuating lever, an actuating spring for said pump lever, a pivotally mounted actuating member coacting with 15 said actuating cam, said cam and actuating member having parts attached to retain the members in engaging position until a pre-determined point in the movement of the cam is reached, a link connecting said actuating member to said pump lever, a plurality 20 of timing cams, a rock shaft provided with an adjustable arm coacting with said timing cams, a control arm on said rock shaft coacting with said actuating member to move it to position to coat with said actuating cam, and a spring connecting said actuating member and control arm so that when the actuating member is released from the actuating cam, it is returned to its inoperative 25 position.

4. In a structure of the class described, the combination of a driving spindle, an actuating cam on said driving spindle, an abradant receptacle, a pump, a pump actuating lever, 35 an actuating member mounted for adjustment to and from operative position to coat with said actuating cam and operatively connected to said pump lever, and a timing means for controlling said actuating member.

5. In a structure of the class described, the combination of a driving spindle, an actuating cam on said driving spindle, an abradant receptacle, a pump, a pump actuating member 45 mounted for adjustment to and from operative position to coat with said actuating cam, a timing means for controlling said actuating member.

6. In a structure of the class described, the 50 combination of a driving spindle provided with a head, a circular spiral inwardly beveled cam on said spindle head, an abradant receptacle mounted on said head within said cam, a frame member depending into said receptacle, an agitator on said frame, a pump mounted on said frame member and adapted to deliver to the work, a pump actuating lever pivoted on said frame member, an actuating spring for said pump lever, a pivotally 55 mounted actuating member beveled to coat with said actuating cam, a link connecting said actuating member to said pump lever, a plurality of timing cams, driving 60 connections therefor to said driving spindle, a rock shaft provided with an adjustable 65

arm coacting with said timing cams, a control arm on said rock shaft coacting with said actuating member to move it to position to coat with said actuating cam, and a spring connecting said actuating member 70 and control arm so that when the actuating member is released from the actuating cam, it is returned to its inoperative position.

7. In a structure of the class described, the combination of a driving spindle provided 75 with a head, a circular spiral inwardly beveled cam on said spindle head, an abradant receptacle mounted on said head within said cam, a frame member depending into said receptacle, an agitator on said frame, a pump mounted on said frame member and adapted 80 to deliver to the work, a pump actuating lever pivoted on said frame member, an actuating spring for said pump lever, a pivotally mounted actuating member beveled to 85 coat with said actuating cam, a link connecting said actuating member to said pump lever, a control arm coacting with said actuating member to move it to position to coat with said actuating cam, and a spring connecting said actuating member and control arm so that when the actuating member is released from the actuating cam, it is returned to its inoperative 90 position.

8. In a structure of the class described, 95 the combination of a driving spindle provided with a head, a circular spiral inwardly beveled cam on said spindle head, an abradant receptacle mounted within said cam, a pump depending into said receptacle, a pump actuating lever, an actuating spring for said pump lever, a pivotally mounted actuating member beveled to coat with said actuating cam, a link connecting said actuating member to said pump lever, a control 100 member coacting with said actuating member to move it to position to coat with said cam, a spring connecting said actuating member and control member so that when the actuating member is released from the 110 actuating cam, it is returned to its inoperative position, and an actuating means for said control arm.

9. In a structure of the class described, 115 the combination of a driving spindle provided with a head, a circular spiral cam on said spindle head, an abradant receptacle mounted on said head within said cam, a frame member depending into said receptacle, an agitator on said frame, a pump mounted on said frame member and adapted to deliver to the work, a pump actuating lever pivoted on said frame member, an actuating spring for said pump lever, an actuating member coacting with said actuating 120 cam, and a link connecting said actuating member to said pump lever.

10. In a structure of the class described, 125 the combination of a driving spindle, an actuating cam on said driving spindle, an

abradant receptacle mounted to rotate therewith, an agitator depending into said receptacle, a pump, a pump actuating lever, an actuating spring for said pump lever, a 5 pivotally mounted actuating member coacting with said actuating cam, a link connecting said actuating member to said pump lever, a plurality of timing cams, a rock shaft provided with an adjustable arm 10 coacting with said timing cams, a control arm on said rock shaft coacting with said actuating member to move it to position to coact with said actuating cam, and a spring connecting said actuating member and control 15 arm so that when the actuating member is released from the actuating cam, it is returned to its inoperative position.

11. In a structure of the class described, the combination of a driving spindle, an 20 actuating cam on said driving spindle, an abradant receptacle, a pump adapted to deliver to the work, a pump actuating lever,

an actuating spring for said pump lever, an actuating member mounted for adjustment to and from operative position to coact with 25 said actuating cam and operatively connected to said pump lever, and a timing means for controlling said actuating member.

12. In a structure of the class described, the combination of an actuating cam, an 30 abradant receptacle, a pump adapted to deliver to the work, a pump actuating member mounted for adjustment to and from operative position to coact with said actuating cam, and a timing means for controlling said 35 actuating member.

In witness whereof, I have hereunto set my hand and seal in the presence of two witnesses.

WALTER G. HASTINGS. [L.S.]
